UNITED STATES PATENT OFFICE.

HAROLD W. HARRIS, OF LA PORTE, INDIANA.

DESIGN FOR A COMBINED FLOOR LAMP AND RADIOCABINET.

Application filed February 4, 1926. Serial No. 16,401. Term of patent 3½ years.

To all whom it may concern:

Be it known that I, HAROLD W. HARRIS, a citizen of the United States, residing at La Porte, in the county of La Porte and State of Indiana, have invented a new, original, and ornamental Design for Combined Floor Lamp and Radiocabinet, of which the following is a specification, reference being had to the accompanying drawing, forming part thereof.

The figure is a perspective view of a combined floor lamp and radiocabinet of my design.

I claim

The ornamental design for a combined floor lamp and radiocabinet, as shown.

HAROLD W. HARRIS.
